PNEUMATIC COUNTER WITH SPRING RETURN

BACKGROUND OF THE INVENTION

This invention relates to counters and more particularly to pneumatic counters which are extremely reliable, simple, and inexpensive to manufacture, easy to assemble and service; and applicable in virtually any environment where it is desirable to count, i.e., accumulate the consecutive reception of pneumatic pulses representative of a particular parameter being monitored.

In many situations where it is desirable to monitor a particular parameter at a remote location, it is preferable and sometimes even necessary that fluidic means, rather than electrical means be utilized to convey the necessary information. An example of such fluidic telemetering apparatus is disclosed in U.S. Pat. No. 3,352,488 issued Nov. 14, 1967 to G. B. Greene.

In the Greene patent, there is disclosed a fluidic telemetering apparatus for use with water meters, utility meters and the like. The Greene system employs a transmitter at the site of the meter being monitored and a receiver of similar construction, positioned at some accessible location relatively far removed from the normally inaccessible meter. The transmitter in the Greene system includes a pair of expandable bellows one of which is expanded and one of which is collapsed by direct mechanical actuation representative of the water flow through the meter. The fluidic pulses generated thereby are then transmitted by a pair of conduits to a pair of expandable chambers which in converse relationship, expand and collapse respectively to generate mechanical motion utilized to advance the counting wheel located in the receiver. Although the receiving end of the Greene patent functions extremely well in the particular Greene system, it is extremely limited as a general purpose pneumatic counter since the dual bellows arrangement thereof dictates that it be used exclusively in conjunction with a transmitting end which similarly includes a pair of expandable bellows.

However, in many fluidic telemetering situations, the transmitting end of the system is, by previous design, not equipped with a double bellows arrangement, or because of other considerations, can only be arranged to produce consecutive single fluidic pulses representative of the particular parameter being monitored. Thus as is, the Greene receiving system with its two conduits—two bellows structure is completely useless in these situations.

SUMMARY OF THE INVENTION

With a view toward utilizing existing machinery, parts, and know-how, the instant inventors have labored to redesign the Greene receiver in such a manner as to produce a simple, inexpensive, extremely reliable, universal pneumatic counter which will operate on the reception of single, discrete fluid pulses representative of a particular parameter being monitored.

In accordance with the broad aspect of the instant invention, one of the two bellows of the aforescribed Greene receiver has been eliminated and, in effect, replaced by biasing means which will return a rocker arm (which has been previously rotated by the remaining expandable chamber), to its initial position upon the discontinuance of the reception of the fluidic pulses being counted. Through actuating means to be described in greater detail, the back and forth movement of the rocker arm is utilized to step a counter wheel and thereby provide an indication of the parameter being monitored at the transmitting end of the particular system in which the counter finds application. Thus with this relatively simple, but long unthought of idea, the basic Greene type of receiver arrangement becomes a universally applicable pneumatic counter useful in any telemetering system which produces only single pulses.

Despite the apparent workability of the basic concept of the instant invention, its implementation presented other problems which have been overcome in a particular manner which represents significant inventive contribution in and of

itself. For example, and with reference to FIG. 2 of the aforementioned Greene U.S. Pat. No. 3,352,488, once the instant inventors had conceived the idea of eliminating one of the bellows in the receiver of the Greene system, one of the means of attachment of the rocker arm 91, 92 to the frame 90 was eliminated, and there became a need for a more positive fulcrum or pivotal connection between the rocker arm of the new invention and the rocker arm supporting means or A-frame therefor. Such pivotal connection had to be established by a direct assembly which would be simple, inexpensive to manufacture, and easy to assemble even by relatively unskilled personnel. In accordance with a secondary aspect of the instant invention, and as will be described in greater detail, the aforesaid pivotal connection is established by providing the rocker arm and the rocker arm supporting means with a pair of upturned flanges and ears respectively, each including an aperture, all of which are aligned such that a simple pivotal pin may be directly inserted therethrough. As a further feature, such ears and flanges respectively are integrally formed on their respective members thereby simplifying manufacture by facilitating a simple bending and punching operation on a minimum number of pieces.

As a further feature, completely new actuating means have been provided to mechanically interconnect the movement of the aforementioned rocker arm with the counterwheel which accumulates or counts the pulses received by the expandable chamber. Thus, and as will be further described, a generally U-shaped member is provided one leg of which coacts with the driving gear of the counterwheel and the other leg of which includes an elongated slot which receives the end portion of a center leg of the oscillating rocking arm. The U-shaped member is pivotally connected to the frame and rotates about its pivotal axis in response to movement of the rocker arm to consecutively advance the counterwheel. Such simplified construction has been found to be a vast improvement over the reciprocating bar and necessary guide therefor which were required in the aforementioned Greene system.

Accordingly, it is an object of the instant invention to provide a pneumatic counter useful in an endless variety of telemetering systems which produce consecutive single pulses representative of a particular parameter being monitored.

Another object of the instant invention is to provide such a pneumatic counter which implements the above-noted object by the provision of many engineering improvements with respect to similar devices in the prior art.

Another object of the instant invention is to provide such a pneumatic counter which is simple and inexpensive to manufacture, extremely reliable, easy to assemble even by unskilled personnel, and of such basic design as to take advantage of existing manufacturing equipment, inventory parts and existing know-how.

These and other objects of the instant invention may be had by referring to the following description in which:

FIG. 1 is a plan view, with outer casing removed, of a pneumatic counter constructed in accordance with the principles of the instant invention;

FIG. 2 is a view, partly in section, taking along the lines 2—2 of FIG. 1;

FIG. 3 is a perspective view of the rocker arm of the instant invention;

FIG. 4 is a perspective view, partly in section of the pneumatic counter of the instant invention; and

FIGS. 5 and 6 are somewhat schematic views illustrating the principals of operation of the instant invention.

Turning to the FIGS. wherein like numerals indicate like parts, there is shown the pneumatic counter 10 of the instant invention, with the exterior casing thereof removed for the sake of drawing clarity. Broadly speaking, the counter 10 includes a frame 12 which as best seen in FIG. 4 is of generally U-shaped construction. A generally A-shaped rocker arm supporting means 14, having side portions 16 and 18 and a generally planer upper surface 20, is rigidly secured to the frame 12 by virtue of extending tabs 22 of the side surfaces 16

and 18 being received in slots 24 provided in one leg 26 of the frame 12. As best seen in FIG. 1, the upper planer surface 20 of the A-shaped frame 14 includes integrally upstanding ears 28 in which are provided apertures 30, only one of which is visible in FIG. 4.

The side portion 18 of the rocker arm supporting means 14 carries the panlike fixed portion 32 of a conventional expandible bellows 34, the diaphragmlike expandible portion thereof 36 being secured to an outstanding arm 38 of a rocker arm 40 to be described in greater detail. A fluidic pulse carrying conduit 42 which carries the fluidic pulses representative of the parameter being monitored, is sealingly connected to the panlike portion 32 of the expandible bellows 34 and causes the bellows 34 to expand upon the reception of a fluidic pulse carried by the conduit 42.

As best seen in FIG. 3, the rocker arm 40 is of one-piece integral construction and perhaps is best described as being of W-shaped construction. That is, it includes the aforementioned outstanding leg 38, a depending leg 44, and an oppositely disposed outstanding leg 46 of a similar shape to the leg 38 but laterally offset with respect thereto. The base portions 48 of the rocker arm 40 which join the outstanding legs 38 and 46 to the central leg 44 include integrally upstanding flanges 50 each of which includes an aperture 52 therethrough.

As best seen in FIGS. 1 and 4, the rocker arm 40 is so disposed with respect to the rocker arm supporting means 14, that the central leg 44 is disposed between the side portions 16 and 18 of the rocker arm supporting means 14, and the legs 38 and 46 of the rocker arm extend outside of the side surfaces 16 and 18. The rocker arm 40 is maintained in this relative position by a pivotal connection established between the rocker arm 40 and the rocker arm supporting means 14 by means of a pivot pin 54 which passes through the four apertures provided in the pairs of upstanding ears and flanges 28 and 50 respectively of the rocker arm supporting means 14 and the rocker arm 40.

The center leg 44 of the rocker arm 40 includes a generally narrower terminating end portion 56 which as best seen in FIG. 4, is received within a slot 56 provided in one leg 60 of a generally U-shaped actuating member 62. The other leg 64 of the actuating member 62 is somewhat longer than the leg 60 and terminates in a generally C-shaped pawl portion which engages the drive gear 66 of a conventional counter wheel 68. The actuating member 62 is pivotally mounted for rotation about an axis 70 which passes through its legs 60 and 64 and is maintained in the opposite sides of the frame 12.

To complete the counter, biasing means in the form of a small spring 72 is secured at one end to the side surface 16 of the rocker arm supporting means 14 and at its other end to the center leg 44 of the rocker arm 40.

The operation of the pneumatic counter 10 of the instant invention should now be apparent. Specifically, and with reference to FIGS. 5 and 6, when a fluidic pulse carried by the conduit 42 is received by the expandible chamber means 34, the diaphragm portion 36 thereof expands to rotate the rocker arm 40 in a counterclockwise direction depicted by the arrowhead 74 in FIG. 6. It will be appreciated that as the rocker arm 40 rotates, the center leg 44 thereof causes the biasing spring 72 to be extended. Upon the disappearance of the fluidic pulse, the spring 72 causes the rocker arm 40 to rotate back to its initial position illustrated in FIG. 5 thereby simultaneously collapsing the diaphragm portion of the expandable chamber 34.

With reference to FIG. 4, as the center leg 44 of the rocker arm 40 experiences its counterclockwise and then clockwise rotation about the pivot pin 54, the actuating member 62 connected thereto will experience clockwise and then counterclockwise rotation about the axis 70 carried by the frame 12. Accordingly, the longer leg 64 of the actuating member 62 will oscillate in similar fashion and the pawl portion thereof will advance the gear 66 and hence the counterwheel 68. It will be appreciated that the counterwheel gear combination is

of conventional design permitting unidirectional advancement only as the pawl portion of leg 64 continually oscillates.

It will be appreciated that the above-described counter 10 is of extremely simplified construction, easily assembled by even unskilled personnel and especially adapted to register the reception of fluidic pulses generated in a single line conduit. It should also be apparent that the establishment of the pivotal connection between the rocker arm and rocker arm supporting means established by virtue of the cooperating ears and flanges respectively provides a simple arrangement for maintaining the desired orientation of these parts with respect to one another.

Finally, the fact that the various parts such as the rocker arm and the rocker arm supporting means can be fabricated by appropriate bending, cutting, and punching from one-piece, flat stock material significantly reduces manufacturing costs and thereby permits the device to economically implement the desired result.

Although this invention has been described with respect to its preferred embodiments, it should be understood that many variations and modifications will now be obvious to those skilled in the art, and it is preferred, therefore, that the scope of the invention be limited, not by the specific disclosure herein, only by the appended claims.

What is claimed is:

1. A pneumatic counter comprising:
a frame;
rocker arm supporting means connected to said frame for supporting a rocker arm;
a rocker arm pivotally connected to said rocker arm supporting means, said rocker arm having at least one outstanding portion thereof;
expandible chamber means secured between said rocker arm supporting means and said one outstanding portion of said rocker arm for rotating said rocker arm in a first direction in response to a pneumatic pulse being received by said expandible chamber means;
biasing means secured at one end to said rocker arm supporting means and its other end to said rocker arm for rotating said rocker arm in a second direction opposite said first direction upon the discontinuance of the reception of said pneumatic pulse by said expandible chamber means;
counting means;
actuating means operatively connecting said rocker arm and said counting means for advancing said counting means in response to rotation of said rocker arm;
wherein said rocker arm includes a depending leg to which said other end of said biasing means is secured and to which said actuating means is connected; and
wherein said actuating means comprises a generally U-shaped member rotatably mounted with respect to said frame, one leg of said U-shaped member operatively connected to said counting means, the other leg of said U-shaped member having a slot within which is received said depending leg of said rocker arm.

2. A pneumatic counter comprising:
a frame;
rocker arm supporting means connected to said frame for supporting a rocker arm;
a rocker arm pivotally connected to said rocker arm supporting means, said rocker arm having at least one outstanding portion thereof; expandible chamber means secured between said rocker arm supporting means and said one outstanding portion of said rocker arm for rotating said rocker arm in a first direction in response to a pneumatic pulse being received by said expandible chamber means;

biasing means secured at one end to said rocker arm supporting means and at its other end to said rocker arm for rotating said rocker arm in a second direction opposite said first direction upon the discontinuance of the reception of said pneumatic pulse by said expandible chamber means;

counting means;
 actuating means operatively connecting said rocker arm and said counting means for advancing said counting means in response to rotation of said rocker arm;
 wherein said rocker arm supporting means includes a pair of upturned ears each of which includes an aperture therethrough; said rocker arm includes a pair of upturned flanges having apertures aligned with the apertures in said ears;
 further including a pivot pin passing through the apertures in said ears and flanges for establishing the pivoted connection between said rocker arm supporting means and said rocker arm; and
 wherein said actuating means comprises a generally U-shaped member rotatably mounted with respect to said 15

frame, one leg of said U-shaped member operatively connected to said counting means, the other leg of said U-shaped member having a slot within which is received said depending leg of said rocker arm.

3. The pneumatic counter of claim 2 wherein said rocker arm supporting means is generally A-shaped and includes a pair of side portions and a generally planar upper surface, said upturned ears of said rocker arm supporting means integrally extending upward from said generally planar upper surface.

4. The pneumatic counter of claim 2 wherein said rocker arm is a one-piece member.

5. The pneumatic counter of claim 4 wherein said rocker arm supporting means is a one-piece member.
